METHOD OF MANUFACTURING GARMENT
BAGS

Benjamin A. Levitt, Newark, N. J., assignor to
A. L. Siegel Co., Inc., New York, N. Y., a corpora-
tion of New York

Application February 27, 1947, Serial No. 731,206

9 Claims. (Cl. 112—262)

1

This invention relates to an improved method of manufacturing a garment bag.

Garment bags into which various articles of clothing may be placed for protective purposes, which bags are adapted themselves to be hung in closets or the like, take many forms. The most common of these forms comprises a rectangular cross-section so that the individual garments may be individually hung and removed from the garment bag preferably through the side thereof without the necessity of removing the entire garment bag from its suspension. Such bags have been formed of cloth and, more recently, of plastic sheeting, the cloth or plastic sheeting defining the walls of the bag and being maintained so as to define a rectangular or any other desired cross-section by means of suitable framework disposed at the top and optionally at the bottom of the bag.

Garment bags of this nature have become exceedingly popular commercial-wise but as constructed heretofore they present certain potential defects which render them more or less inefficient in the attainment of their desired end.

One of the purposes of such bags is to protect the clothing stored therein from the effects of dirt and moisture in the air. Obviously the more seams involved in the formation of the bag the less protection is afforded against these deleterious influences. As ordinarily constructed, the top, bottom, front, back and side walls of the bags are of separate strips or sheets of material each of which is joined to the adjacent strip or sheet at each of its edges by means of a seam. This means that a bag with a rectangular cross-section will have twelve seams. Even if the front, back and side walls be formed of a single sheet of material suitably joined together at a single seam, the total number of seams in the garment bag is only reduced to nine.

Moreover, those seams which are most susceptible to spreading or unsealing, to wit, the seams at the edges of the top and bottom walls of the container, are not eliminated. While the weight of the bag itself is generally inconsequential, it quite often happens that garments become disengaged from within the bag and fall to the bottom thereof and the far from inconsequential weight of these garments is then supported almost exclusively by the seams joining the top and bottom walls to the other walls. This strain is applied directly to the seams under discussion, particularly because those seams conform to the configuration of the top and bottom frames which give shape to the garment bag.

2

In addition to these inherent constructional defects, impelling economic considerations mitigate against the prior art construction. A very substantial portion of the cost of manufacture of a garment bag resides in the assembly thereof and in particular in the seaming thereof. Thus, any method of construction which would minimize the number of seams is obviously commercially advantageous. In the past it has been necessary, when joining the top or bottom wall of a garment bag to the front, back and side walls thereof, to form four separate seams corresponding to the four sides of the top or bottom surface in four separate operations. As soon as one seam was completed, it was necessary for an operator to turn the fabric 90° so that the next seam might be formed. To attach both the top and bottom, eight separate operations were necessary.

Moreover, the problem of providing a plurality of sheets of different sizes called for considerable tailoring work and required an extensive inventory.

It is the prime object of the present invention to provide a novel method of manufacture of a garment bag having a minimum of seams.

It is yet another object of the present invention to provide such a method which results in a bag in which the seams are so located with respect to the framework of the garment bag as to minimize the strains applied thereto during use of the bag.

Another object of this invention is to provide such a method in which a minimum of separate sheets of material, and in the preferred embodiment, but a single sheet, is utilized.

It is an important object of the present invention to provide a method of manufacture for a garment bag having top, bottom and side walls in which the seam effective to form and join the top or bottom wall with the side walls is linear and consequently may be made in a single operation, thus materially and significantly reducing manufacturing time and cost.

While the present invention is herein described with particular reference to the manufacture of a garment bag, it will be appreciated that in its broader aspects it relates to any hollow container formed of flexible material and to the method of forming the same. It will also be apparent that when the term "seaming" is used, any type of seaming may be employed. As herein specifically described, the seaming is accomplished by means of a stitching or sewing operation, but it will be appreciated that when thermoplastic sheeting is employed, the seaming may be ac-

complished by heat-sealing, either alone or in addition to stitching. Other variations of seaming will no doubt suggest themselves, such as the use of adhesives or softening solvents.

To the accomplishment of the foregoing objects and such other objects as may hereinafter appear, the present invention relates to the method of constructing a garment bag as defined in the appended claims as set forth in this specification, taken together with the accompanying drawings, in which:

Figs. 1, 2 and 3 represent elevational views of successive stages in the formation of the garment bag of the present invention from a single flexible sheet;

Figs. 4, 5 and 6 are top views of Figs. 1, 2 and 3, respectively;

Fig. 7 is a perspective view of one embodiment of the top frame for the garment bag;

Fig. 8 is a similar view of the bottom frame;

Fig. 9 is a perspective view of a completed and expanded garment bag made according to the present invention with parts thereof broken away;

Fig. 10 is a detailed view on enlarged scale of the side wall-top wall joint formed therein; and

Figs. 11 and 12 are views corresponding to Figs. 1 and 2 but showing stages in the formation of a garment bag from a plurality of sheets of flexible material.

The method of making the garment bag of the present invention will first be described, the resultant improved construction of said bag becoming apparent as the method is developed. That method, considered in its broad aspects, comprises superimposing two layers A and B of flexible sheeting (Figs. 1 and 11). This sheeting may be cloth, either plain or ornamented, or any of the well known plastic sheetings now on the market.

The sides C and C' of the two-ply formation thus produced are then folded over the body portion D thereof (Fig. 2) so that at the thus formed edge sections 2 and 4 a four-ply formation is produced. One or both of the end edges E or E', which edges are preferably linear, are then seamed as by stitching 6, this seam including all of the plies of the folded edge sections 2 and 4 and of the body D. The resultant structure is then turned inside out.

When the thus formed bag is caused to expand so that its top and bottom surfaces conform to the desired outline, as by the use of top frame 8 and bottom frame 10, it is found that for example the top and bottom walls F and F' of the bag are each composed of two portions G and H (Figs. 9 and 10), each of which are integral extensions of the front and back walls 12 and 14 respectively, these two portions being joined together by a single straight seam 16 intermediate said end wall F.

It will be noted that by this method of construction only a single seam is necessary to form the top of the garment bag, this seam being linear so that it may be made in a single seaming operation, thus materially decreasing the cost of manufacture of the bag, and that the seam is so located on the finished garment bag that any strains imposed by the weight of articles on the bottom of said bag is insulated from said seam by the action of the frames 8 or 10, the frames taking much of the strain and thus ensuring that the seam will remain firm and thus prolong the life of the bag and enhance its protective effect.

Figs. 1 through 10 illustrate the preferred embodiment of the present invention in which a complete garment bag is manufactured by forming but three seams. A single sheet 18 of flexible material is first reversely folded on itself so as to define the two-ply formation illustrated in Figs. 1 and 4. The side C' thereof is initially open and that side therefore must be seamed as by the stitching 20, this seaming operation being so carried out as to incorporate in the thus formed seam an opening and closing means generally designated 22 which may specifically take the form of a zipper or slide fastener as illustrated in Fig. 9. This opening and closing means 22 provides for access to the interior of the container for removal and insertion of garments and also, in the formation of the container, provides an opening for a purpose hereinafter to be described.

The sheet 18 is preferably provided with a pair of eyelets 24 for cooperation with the suspending hooks 26 of the frame 8, and the sheet 18 may be interiorly reinforced by means of fabric tabs 28.

As illustrated in Figs. 2 and 5, the sides C and C' of the folded sheet of Fig. 1 are folded over the body D thereof an amount equal to one-half of the desired depth of the container, that is to say, one-half the desired width of the top wall F and of the side walls 30 thereof. The top and bottom end edges E and E' of the thus folded formation are then linearly seamed as by the stitching 6 and 6' (Figs. 2 and 5). The thus formed object is then turned inside out via the opening in side C' provided by the opening and closing means 22. This condition is illustrated in Figs. 3 and 6 and represents a collapsed garment bag having a front wall A, a rear wall B and infolded side walls 30, the top and bottom end edges E and E' of all of said walls being linearly seamed together.

The collapsed garment bag of Fig. 3 may be expanded and caused to assume its desired shape by inserting therein, through the opening provided by the opening and closing means 22, the top and bottom frames 8 and 10. The former of these may consist of a metal framework 32 of desired shape having a cross-bar 34 provided with a plurality of corrugations 36 adapted to receive the hooks of hangers on which garments are mounted so that said garments may be suspended within the garment bag, and with suspending hooks 26 so mounted as to project up from the cross-bar 34 through the eyelets 24 of the sheet 18 so that the garment bag itself and the garments stored therein may all be suspended from the hooks 26. The frame 10 may be a thin cardboard, plywood or metal sheet of appropriate shape.

The construction of the garment bag as described is such that, if properly designed, the bag itself upon expansion will closely conform to the frames 8 and 10 without the necessity of any special steps. It will be noted that when this conformation has taken place, tucked-in portions 38, best shown in Fig. 10, will form at the junction of the side walls 30 and the top and bottom walls F and F'. These tucked-in portions constitute integral extensions of the side walls 30.

The garment bag of Fig. 9 has by this method been constructed of a single flexible sheet with but three seams, one intermediate of one of the side walls 30 and containing the opening and closing means 22 and one intermediate each of the top and bottom walls F and F', the latter

being defined by the stitching 6 and 6' as here illustrated. The saving in time and expense involved in forming three rather than twelve seams is obvious. Furthermore, both of the top and bottom seams 16 and 16' are inset from the edges of the top and bottom frames 8 and 10 so that any strain applied to the bag because of articles resting on the bottom thereof is primarily resisted by the integral and unseamed portions of fabric which are adjacent to the metal framework 32 or the sides of the bottom frame 10. The seams 16 and 16' will therefore be insulated from said strain so that the life of the bag and its protective action toward the garments stored therein are materially increased.

Although to form a container from a plurality of rather than from a single sheet involves the making of at least one additional seam, and to that limited extent detracts from the benefits of the present invention, it is sometimes necessary or desirable that this mode of construction be employed as, for example, where single sheets of sufficient size for a complete container cannot commercially or economically be obtained. The first two stages of such a mode of construction are illustrated in Figs. 11 and 12, which correspond to Figs. 1 and 2, and it will be apparent that the only difference involved over the method previously described is that the edge C must be seamed as by stitching 20'. Otherwise the stages of construction are identical and need not be here repeated. It will also be apparent that each of the individual sheets which are superimposed one or the other may itself be formed of any desired number of individual strips or sheets.

By the method of construction above described a garment bag or other hollow container may be more expeditiously and economically formed than has heretofore been possible and the container produced thereby is possessed of desirable structural features which eliminate or mitigate many of the defects inherent in containers of this type which have heretofore been manufactured. Not only is the container thus produced enhanced in strength and durability by virtue of the location of its seams, but its protective action is also intensified by virtue of the minimum number of seams embodied in its construction and by virtue of the fact that they are so located that their tendency to part is minimized.

The particular embodiment of container here illustrated, a garment bag of conventional shape, is merely illustrative of the many applications to which my invention can be put and therefore many variations can be made in the details of the method steps and constructional features here shown without departing from the spirit of the invention as defined in the following claims.

I claim:

1. The method of linearly seaming a surface of a container formed from flexible sheeting, which comprises superimposing one layer of said sheeting over another producing thereby a two-ply formation, folding both sides of said two-ply formation over the body thereof, linearly seaming together all of the plies of the folded sides and body at an end edge of said formation, and then turning the thus formed object inside out.

2. The method of linearly seaming surfaces of a container formed from flexible sheeting which comprises superimposing one layer of said sheeting over another producing thereby a two-ply formation, folding both sides of said two-

ply formation over the body thereof, linearly seaming together all of the plies of the folded sides and body at the top and bottom end edges of said formation, and then turning the thus formed object inside out.

3. The method of linearly seaming surfaces of a container formed from flexible sheeting which comprises superimposing one layer of said sheeting over another producing thereby a two-ply formation, one side of said formation having an opening therein, folding both sides of said two-ply formation over the body thereof, linearly seaming together all of the plies of the folded sides and body at the top and bottom end edges of said formation, and then turning the thus formed object inside out via said opening.

4. The method of linearly seaming a surface of a container formed from flexible sheeting to produce the container end which comprises superimposing one layer of said sheeting over another producing thereby a two-ply formation, folding each side of said two-ply formation over the body thereof an amount equal to one-half of the desired depth of the container end, linearly seaming together all of the plies of the folded sides and body at the end edge of said formation, and then turning the thus formed object inside out, the container end being thereafter formed by spreading the formed walls of the container.

5. The method of linearly seaming a surface of a container formed from a single flexible sheet which comprises folding said sheet in half and producing thereby a two-ply formation, folding both sides of said two-ply formation over the body thereof, linearly seaming together all of the plies of the folded sides and body at an end edge of said formation, turning the thus formed object inside out, and forming the container end by spreading the formed walls of the container.

6. The method of forming a container having a rectangular cross-section from flexible sheeting which comprises superimposing one layer of said sheeting over another and separate layer producing thereby a two-ply formation, seaming both open side edges of said two-ply formation while including an opening and closing means in one of said side edges, folding both sides of said two-ply formation over the body thereof, linearly seaming together all of the plies of the folded sides and body at the top and at the bottom end edges of said formation, turning the thus formed object inside out, and spreading the formed walls so as to give the container a rectangular cross-section.

7. The method of forming a container having a rectangular cross-section from a single flexible sheet which comprises folding said sheet in half producing thereby a two-ply formation, seaming the open side edge while including therein an opening and closing means, folding both sides of said two-ply formation over the body thereof, linearly seaming together all of the plies of the folded sides and body at the top and at the bottom end edges of said formation, turning the thus formed object inside out, and spreading the formed walls so as to give the container a rectangular cross-section.

8. The method of forming a container having a rectangular cross-section from flexible sheeting which comprises superimposing one layer of said sheeting over another and separate layer producing thereby a two-ply formation, seaming both open side edges of said two-ply formation while including an opening and closing means in one of said side edges, folding both sides

7
of said two-ply formation over the body thereof, linearly seaming together all of the plies of the folded sides and body at the top and bottom end edges of said formation, turning the thus formed object inside out, inserting appropriately shaped top and bottom frames therein, and causing the top and bottom of said container to conform thereto.

9. The method of forming a container having a rectangular cross-section from a single flexible sheet which comprises folding said sheet in half producing thereby a two-ply formation, seaming the open side edge while including therein an opening and closing means, folding the sides of said two-ply formation over the body thereof, linearly seaming together all of the plies of the folded sides and body at the top and at the bottom end edges of said formation, turning the

10

thus formed object inside out, inserting appropriately shaped top and bottom frames therein, and causing the top and bottom of said container to conform thereto.
